COIN RETURN

Bernhard C. Grunig, Chicago, Ill., assignor to
 A. B. T. Manufacturing Corp., Chicago, Ill., a
 corporation of Illinois

Application July 29, 1940, Serial No. 348,133

4 Claims. (Cl. 194—63)

This invention relates to coin testing devices and has for its principal object the provision of a coin return mechanism for use with the type of coin control which employs a coin carrier to move a coin and release a latch.

A particular feature of the coin return relates to the provision of mechanism for releasing the latch to permit a coin to move out of the carrier, and means for preventing operation of the control while the latch is thus released.

Viewed from another aspect, it is an object of the invention to provide a combination including a coin testing device having a return or scavenging gate and a manually operated member for operating the gate to clear the device of slugs or other unacceptable coin elements, together with an operating control including a coin carrier adapted to receive coins from the coin testing device and move the coin into engagement with a latch to release the latter, together with coin return means controlled by the scavenging or return operating member for moving the latch into ineffective position so that a coin in the carrier will be returned or released, and simultaneously with the release of the latch another latch will latch the main control against effective operation.

Another object relates to the provision of a novel return gate which normally blocks access of defrauding tools to the latch mechanism through the return exit, but which is moved into open position each time the coin return operating member is actuated.

Other objects, advantages and novel aspects of the invention reside in certain details of construction as well as the cooperative relationship of the component parts of the illustrative embodiment described hereinafter in view of the annexed drawing, in which:

Fig. 1 is a perspective of the control unit with a portion of the casing broken away;

Fig. 2 is a fragmentary vertical section to enlarged scale along lines 2—2 of Fig. 1;

Fig. 3 is a fragmentary horizontal section looking down along lines 3—3 of Fig. 2 turned 90° clockwise;

Fig. 4 is a fragmentary vertical section looking toward the return gate in the direction of lines 4—4 of Fig. 3;

Fig. 5 is a perspective view of the latch mechanism and return gate.

The complete control unit shown in Fig. 1 includes a housing or casing 10 having a coin entrance 11 at its top and a coin return receptacle 12 at its bottom, together with a main operating

knob 13 and a coin return push button 14, the unit being adapted for mounting on some device to be controlled thereby and set into operation by manipulation of the knob 13 following deposit of a proper coin in the unit.

Disposed within the casing 10 in the upper part thereof is a coin testing unit 15 of the gravity chute type including a descending coin passage 16 having an entrance portion 17 in register with 10 the deposit opening 11, the passage dividing at the lower part of the chute into an acceptance exit 18 and a reject exit 19, there being certain testing instrumentalities known in the art, and therefore not shown in detail herein, for influencing the selective movement of the coin into the exits 18 or 19, depending upon certain characteristics of the coin determining whether the same is acceptable or not.

One of the testing instrumentalities in the 20 chute may be in the nature of a feeler 20, pivoted as at 21, on a movable wall section 22 of the chute, which section is more commonly known as a return or scavenging gate. An offset nose portion 23 of the feeler projects through an opening 24 in the gate and into the passage 16 to engage the side of a coin moving down the chute, with the object of projecting into certain openings or surface irregularities in an unacceptable coin to arrest the same.

25 In order to clear the chute of coins arrested as aforesaid, the movable member or gate is pivoted about its hinge connections 25 by actuation of the return button 14, the lower end portion 14a of which bears against a vertically reciprocable lever 26 (Fig. 1) having an arm portion 27 which engages a cam roller 28 and swings the gate outwardly from its normal position shown in Fig. 1, so that the bottom edge portion 22a of the gate will swing away from the side of the 30 chute over the mouth 29 of a return chute 30 to free the arrested coin for movement into the return exit 12.

In practice, testing chutes of the type above described include additional testing instrumentalities, such as a magnet, not shown herein, but also capable of arresting a coin in that section of the coin passage 16 which is opposite the gate 22, and these coins are likewise discharged from the chute by opening movement of the gate in a manner well known in the art.

Assuming that a coin has been accepted by the chute and directed into the acceptance exit 18, it will lodge in the control mechanism which includes a shaft 13a on which is fixed a rockable or oscillable coin carrier 35 (Figs. 2 and 5) pro-

vided with a downwardly inclined coin groove 36 into which an accepted coin element C drops from the chute.

The coin carrier is normally latched against effective oscillation or movement by action of a latch arm 37 pivoted as at 38 and provided with a pin 39 engaging in a latch notch 40 in the carrier, a spring 41 urging the latch arm yieldably into normally latched condition, attention being called to the fact that the notch 40 is oversized to permit a limited idle movement of the carrier 35 while in latched condition.

The latch pin 39 is disposed at one side of the acceptance exit 18 opposite a shoulder 42 in the carrier, so that the coin C drops between the pin and the shoulder from the chute, in moving into the carrier. When an attempt is made to turn the knob 13 of shaft 13a, the carrier urges the coin C against the latch pin 39 and pivots the lever arm 37 to withdraw the pin entirely from latching engagement with the carrier. As soon as the carrier has turned the coin C beneath pin 39, the coin is free to move from the carrier by gravity from the end 36a of the carrier and into a suitable collection box.

It is frequently desired by the patron that he have his coin returned to him after depositing the same, especially where vending machines are involved and include a plurality of classes of merchandise from which a selection may be made, the return being desired where the patron changes his mind after depositing the coin or possibly makes a mistake in the first instance in selecting a deposit opening, or, for any other legitimate reason, desires to have his coin returned.

Means for effecting return of the coin includes an arrangement particularly illustrated in Fig. 5 wherein there is provided a return lever 50, pivoted as at 51 and having an offset operating connection 50a operatively connected as at 52 with a lower end portion 26a of the scavenger operating lever so that the return lever 50 will be rocked each time the scavenging button 14 is depressed. The return lever includes a latch releasing arm or projection 50b having an offset end portion 50c which engages beneath the latch pin 39 when the return lever is rocked by the scavenging mechanism, with the result that the latch arm is raised from the carrier a distance sufficient to permit the coin to gravitate toward the end 36a of the carrier and through a blocking gate passage 53 into the return cup 12.

Since the latch is released by action of the scavenging or main return mechanism, the control device, including knob 13, is free and could be manipulated to procure an operation of the controlled machine. To prevent this, the return lever 50 is provided with a latch arm 50d which is rocked into position to engage with a locking pin 54 on the carrier, thus preventing movement of the carrier out of normal position so long as the scavenging mechanism remains operated.

In order to prevent insertion of defrauding instrumentalities through the blocking gate opening 53 by manipulation through the return cup 12, there is provided a fraud-preventive blocking gate 55 (Figs. 4 and 5) in which the return passage 53 is formed, the gate having opposite edge portions 56 turned over to provide grooves slidably engaging the upper and lower edge portions of a stationary blocking plate 57 in which there is a companion return opening 53a (Fig. 4). The return gate is disposed in a normal condition by spring means 58 which disposes the return pas-

sage 53 out of register with the companion passage 53a in the stationary plate, thus preventing the insertion of wires or other defrauding instrumentalities from the return cup beneath the latch arm in an effort to free the latter fraudulently.

Means is provided to effect opening of the return gate with each operation of the return mechanism, this means including the provision of an offset cam arm 55a on the blocking gate. A cam roller 60 is carried on an offset arm 61 secured to the lower end portion 26a of the scavenger operating lever, and this roller engages with an upper portion 55b of the cam arm 55a and moves the blocking gate into non-registering position relative to the passage 53a. When the scavenger lever 26 is depressed, roller 60 moves opposite a curved portion 55c in the cam arm and permits the gate 55 to be moved by spring 58 into a position where the passages 53 and 53a are in register so that the coin to be returned may roll from the end 36a into the return cup 12.

The full stroke movements of the coin carrier 35, made when the latch is released either by a coin or operation of the return mechanism, is assured by operation of a usual form of full stroke dog 65 cooperable with tooth formations 66 in the periphery of the carrier, the arrangement being such that once the carrier has been moved a substantial amount from latched position (other than in its normal idle stroke motion), the carrier must be turned through a complete displacement before it can be returned.

The various advantages and objects of the invention may be accomplished by modifications of the particular embodiment specifically described herein, and it is intended that the appended claims shall include all equivalent arrangements fairly coming within their call.

Having thus described my invention, what I claim as new and desire to protect by Letters Patent is:

1. In a coin control device including an operating control and a coin carrier actuated thereby together with a latch normally restraining the carrier against effective movement but permitting a limited idle movement thereof, said latch normally holding a deposited coin in said carrier and being adapted to be cammed into non-latching position with respect to said carrier by a coin when a coin is disposed in the aforesaid position in the carrier and the latter is actuated by the operating control, the combination with said carrier of coin return means including a return operating member and mechanism operatively associated therewith and actuated thereby for moving said latch into non-latching position and out of coin holding position as aforesaid and for simultaneously latching the carrier against effective movement.

2. In a coin control including an operating member and a coin carrier moved thereby together with a latch normally latching the carrier against effective movement and for holding a coin deposited in said carrier in a normal position, said latch being adapted to be moved into ineffective position by said coin deposited in the carrier, the combination with said carrier and latch of coin return means including a return lever arranged for movement from a normal position to move said latch out of latching position and said coin holding position to permit a deposited coin to gravitate beyond said normal position to a return chute, together with a latching

arm moved into latching engagement with means on said carrier simultaneously with the movement of said latch into non-latching position, and mechanism for moving said return lever into and out of normal position.

3. In a device of the class described, a coin carrier adapted to receive coin elements, a latch normally latching said carrier against effective movement and normally holding a deposited coin in an effective position, said latch being engaged and moved by a coin in the carrier into non-latching position responsive to movement of the coin by the carrier, said coin being free to gravitate from the carrier when said latch is in non-latching position, means yieldably urging said latch into latching position, means for moving said latch into non-latching position to permit a coin to gravitate as aforesaid, and means co-acting with said last-mentioned means for latching the carrier against effective movement when said latch is moved into non-latching position as aforesaid.

4. In a device of the class described including a main operating control, a coin carrier oscillated by said control and adapted to receive coin elements, means providing a return passage for a coin element gravitating from the carrier, a latch normally latching said carrier against effective movement but permitting limited idle movement thereof, said latch adapted to hold a coin element received within said coin carrier and adapted to be cammed into a non-latching position by oscillation of said carrier with a coin positioned as aforesaid, a movable blocking member normally blocking said return passage, coin return means for moving said latch out of latching position and out of coin holding position and including a secondary latch adapted to engage said coin carrier independently of said first-mentioned latch, means coacting with said coin return means for moving said blocking member into non-blocking position, and mechanism for actuating said coin-return means.

BERNHARD C. GRUNIG.
